UNITED STATES PATENT OFFICE

2,197,390

ROAD GRADER

Franklin E. Arndt, Galion, Ohio, assignor to The Galion Iron Works and Manufacturing Company, a corporation of Ohio

Application February 21, 1935, Serial No. 7,535
Renewed August 1, 1939

33 Claims. (Cl. 37—156)

My invention relates to road graders, and one of its objects is the provision of improved and efficient means for adjusting the mold-board of a road grader to an upright or approximately upright bank-cutting position and holding the same in such adjusted position during operation.

A further object of the invention is the provision of mechanism comprising interlocking worm gearing for effecting the shifting of the rear end of the drawbar laterally relatively to the grader frame.

Another object of the invention is the provision of improved and efficient mechanism including enclosed nut and screw elements for operating a scarifier.

Another object of the invention is the provision of improved mechanism comprising interlocking worm gearing connected to a perforated or self-cleaning rack bar, for shifting the rear end of the vehicle frame relatively to the rear supporting wheels.

Another object of the invention is the provision of improved mechanism comprising self-locking worm gearing for varying the leaning of the supporting wheels of a road working machine.

Another object of the invention is the provision of improved mechanism, associated with means for leaning the front wheels of the road-working machine, for varying the elevation of the front end of a drawbar.

Another object of the invention is the provision of means for adjusting either a scarifier or the leaning of the front wheels of a road-working machine.

More particularly, it is the object of the present invention to provide adjustment of the mold-board to a steep bank-cutting position and also adjustment of the leaning of the front wheels and rear wheels so that their rims by digging into the road surface will effectively hold the mold-board to its work in the operating path of travel of the bank-sloping machine.

A further object of the invention is the provision of improved telescopic hanger mechanism for the drawbar carrying a mold-board, to facilitate adjustment of the latter to a steep bank-cutting position or almost upright bank-cutting position.

Other objects of the invention will appear hereinafter, the novel features and combinations being set forth in the appended claims.

In the accompanying drawings,

Fig. 1 is an elevational view embodying my invention;

Fig. 2 is an enlarged plan view partly in section of the gearing for adjusting either the scarifier or the leaning of the front wheels;

Figs. 3 and 4, placed end to end, show an enlarged elevational view of the machine shown in Fig. 1;

Fig. 5 is a sectional elevation on the line 5—5 of Fig. 3, looking forwardly in the direction of the arrows;

Fig. 5^a is a sectional elevational view taken on the line 5^a—5^a of Fig. 3, showing the relation between the mechanism for adjusting the front end of the drawbar and the means for effecting adjustment of the leaning of the front wheels;

Figs. 6 and 7, placed end to end, show a plan view of the machine shown in elevation in Figs. 3 and 4 when placed end to end;

Fig. 8 is an enlarged plan view of the adjustable connections between the rear end of the drawbar and the laterally shifting mechanism comprising the rack gearing shown in Fig. 2;

Fig. 9 is an enlarged view of the self-locking worm gearing connected to the rack gearing for effecting lateral shifting of the rear end of the drawbar;

Fig. 10 is a side elevational view of the machine showing the mold-board in high lift or steep bank-cutting position;

Fig. 11 is an enlarged longitudinal sectional view of one of the extensible hangers; and

Fig. 12 is a rear elevational view of the machine shown in Fig. 10.

As shown in Fig. 1, the main supporting frame 14 is upwardly arched and is supported at its rear end on the wheels 15 and at its front end on the wheels 16. The frame 14 is shown in Figs. 6 and 7 as comprising spaced-apart longitudinal side beams connected by the tubular cross-braces 17, 18, 19 and 19'. It should be particularly noted by referring to Fig. 10 that the front and rear wheels are preferably of metal so that the rims thereof will be sufficiently thin to be able to dig into the road surface when the wheels are leaned in such direction as to resist lateral skidding when the mold-board is in a steep bank-cutting position as shown in Figs. 10 and 12 and under operation by movement of the whole machine along the roadway, as will be more fully explained hereinafter.

The machine shown in the accompanying drawings includes mechanism for the steering of the front wheels, the leaning of the front

wheels and the rear wheels, the shifting of the rear end of the main frame laterally relatively to the rear wheels, the shifting of the mold-board laterally and movement thereof to bank-sloping position, the adjustment of the scarifier, and the variation in elevation of the front end of the drawbar. All of the controls extend to the single operator's station or platform 20 at the rear end of the machine, as shown in Figs. 1, 4, 7, 10 and 12. Although I have shown in the accompanying drawings a pull type of road-working machine comprising a tongue 21, to the front end of which is adapted to be connected a pulling tractor, it should be understood that my improvements hereinafter described are also useful in a power grader comprising a power plant connected to rear traction means for moving the entire machine along the roadway.

The front wheel steering mechanism comprises a driving pinion meshing with the chain 22, the ends of which are connected by means of the links 23 and 24 to the brackets 25, 26 attached to the front axle frame 27. The tongue 21 is pivotally connected to the axle 27 midway between the ends of the latter. When the wheel 28 at the rear end of the machine, as shown in Fig. 1, is rotated, the shaft 29 will transmit rotary motion through the universal joints 30, 31, 32 and the links 33, 34, to the worm gearing 35 in the casing 35', and thus rotate the pinion meshing with the chain 22, and thereby swing the tongue 21 in one direction or the other relatively to the front wheels. A counterbalancing spring 36 is connected to the tongue 21 intermediate its ends and also to an inverted V-shaped cross-piece 37, as shown in Figs. 3 and 5.

In order to effect adjustment of the leaning of the front wheels 16, the crank 38 is pushed toward the left, as viewed in Fig. 2, so that the shaft 39 will carry the pinion 40 into mesh with the gear 41 mounted in the casing 42. The gear 41 is connected to a shaft 41' which is journaled in the bearings 43, 44. The forward end of the shaft 41' is connected by means of a universal joint 45 to a shaft 46 which in turn is connected by the universal joint 47 at the front end of the machine, to the bevel gearing 48 shown in dotted lines in Fig. 3 and in elevation in Fig. 5a. The horizontal bevel gear is keyed to a vertical shaft 49, the lower end of which is connected by means of the universal joint 50 to worm gearing 51 in the casing 51'. This worm gearing 51 is connected to a pinion 52 which meshes with an arcuate rack 53 rigidly secured to the transverse cross-piece 54, the ends of which are pivoted at 55, 56 to the vertical arms 57, 58 of bell cranks comprising axles for the front wheels 16; these bell cranks being pivoted at 59, 60 to the front axle frame 27.

As shown in Fig. 2, when the gear 40 meshes with the gear 41, a spring latch 61 is adapted to enter the circumferential groove 62 in the shaft 39 to hold the gears 40 and 41 in mesh while the crank 38 is being rotated. In a similar manner, the spring latch 61 entering the circumferential groove 63 may be relied on to hold the gears 40 and 64 in mesh while the crank 38 is being rotated. When the gear 40 is out of mesh with the gear 41, the worm gearing 51, being self-locking, may be relied on to lock the front wheels in adjusted leaning positions. This is particularly desirable when the mold-board is operating in steep bank-cutting position so that the rims of the front wheels will be able to resist the lateral thrust exerted on the machine during

operation of the mold-board along a steep bank at one side of the path of travel of the machine.

When the gears 40 and 64 are in mesh and the crank 38 is rotated, rotary motion will be transmitted through the universal joint 65, link 66 and universal joint 67, to the rod 68, the front end of which is screw-threaded as shown at 69 in Fig. 2 through a nut 70 secured rigidly to the tube 71 intermediate the ends of the latter. The rod 68 fits in the slide bearing 72 at the rear end of the tube 71. The front end of the tube 71 may be partially or entirely closed by its connection to the clevis 71' which is pivoted at 73 to the upright arm 74, the lower end of which is secured to a transverse shaft 75 intermediate the ends of the latter.

The ends of the shaft 75 are journaled in bearings 76 (Fig. 1) mounted on top of the beams of the frame 14. To the outer ends of the shaft 75 are secured the rearwardly extending arms 77 at opposite sides of the machine, as shown in Fig. 10. Upright hangers 78, 78 at the opposite sides of the machine are flexibly connected at their upper ends to the rear ends of the arms 77, 77, and the lower ends of the hangers 78, 78 are flexibly connected to opposite sides of the scarifier frame 79 which is pivoted at 80 to the front end of the supporting frame 14. The scarifier teeth 81 are mounted on the cross-piece 82 connecting the lower ends of the two arch shaped scarifier arms 83, 83 which are arched upwardly and are bent outwardly from the side beams of the frame 14 so that the space between the arms 83, 83 will be ample for freedom of adjustment of the mold-board drawbar when the mold-board is to be adjusted to steep bank-cutting position. Counter-balancing springs 84, 84 are connected between the rearwardly extending arms 77, 77 and the lower portion of the hangers 78, 78 which are connected at their lower ends to the scarifier frame 79. It should be understood that the scarifier pivoted at 80 at the front end of the main frame 14 is a rigid unit carrying the scarifier teeth 81, and that the scarifier teeth 81 are adjustable in elevation by turning the crank 38 while the gears 40 and 64 are in mesh. The counter-balancing springs 84, 84 facilitate such adjustment as they act against the gravity of the scarifier.

The rear portion of the rod 68, as shown in Fig. 2, is journaled in the bearing 85 for rotation relatively thereto but is restricted against longitudinal movement in either direction by the collars 86 and 87 on the rod 68. The journal bearing 85 is provided with trunnions 88, 88 mounted for rotation on a horizontal axis in the spaced-apart bracket plates 89, 89 extending rearwardly from the tubular cross-brace 18 and connected at their rear ends to the cross-piece 90 which in turn is secured to the beams of the frame 14. It will thus be seen that when the scarifier teeth 81 are doing work on the roadway, the working thrust will be transmitted upwardly along the hangers 78 tending to rotate the shaft 75 in an anti-clockwise direction as viewed in Fig. 1, thereby exerting a pull through the nut and screw elements 70 and 69 on the rod 68 and its connections to the beams of the frame 14. The bracket plates 89 are in a very efficient position to enable advantage to be taken of the strength of the tubular cross-piece 18 acting as an abutment and cooperating with the cross-piece 90 to effectively anchor the rod 68 and resist the working thrust during the operation of the scarifier.

The mold-board or scraper blade 91 is adjustably but rigidly connected to the circle 92 which is mounted for rotation on the vertical axis of the king bolt 93 relatively to the rear portion of the drawbar frame 94, as shown in Fig. 4. When the latch mechanism between the drawbar frame 94 and the circle 92, comprising the latch pin 95, is released by a pull exerted on the flexibly connected links 96, 97, the wheel 98 may be turned to effect rotation of the circle 92 relatively to the drawbar frame 94. The wheel 98 is connected by means of the rods 99, 100 and the universal joints 101, 102 to the rotatable gear 103, as shown in Fig. 4. When the circle carrying the mold-board or scraper blade is in adjusted position relative to the drawbar frame 94, the latch 95 may be relied on to hold the mold-board in such adjusted relative position. As shown by the expance of the arcuate rack 104 in Fig. 7, the adjustment of the mold-board may be made through a wide angle in either direction not only for road grading purposes but also for steep bank-cutting purposes.

By referring to Figs. 6 and 7, placed end to end, it will be seen that the drawbar frame 94 converges toward its front end so as to be relatively narrow at that portion where it extends between the arms 83, 83 of the scarifier. The rear end of the drawbar 94 may therefore be shifted laterally as hereinafter described, and the mold-board may occupy a steep bank-cutting position without causing any interference between the drawbar frame 94 and the arms 83 of the scarifier.

The front end of the drawbar frame 94 is universally connected to the ring support 105 which is screw-threaded to the rotary screw-threaded element 106. This universal connection between the front end of the drawbar frame 94 and the ring support 105 is effected by means of the yoke 107 which is pivoted to the ring support 105 on the horizontal axis 108, as shown in Figs. 1 and 5. The rear end of the yoke 107 is provided with a rearwardly extending rod 109 which is journaled in the bearing 110 and retained in position by the nut 111 on the rear screw-threaded end of the rod 109.

When the mold-board is moved to steep bank-cutting position, the drawbar frame 94 must be moved from the position shown in Fig. 1 to that shown in Figs. 10 and 12. In order to afford ample clearance between the drawbar frame 94 and the main frame 14 for adjustment from road grading position to steep bank-cutting position, the front end of the drawbar frame is preferably moved to its lowermost position by such rotation of the screw threaded element 106 as to effect downward movement of the supporting ring 105. The mechanism for lowering the front end of the drawbar frame 94 relatively to the main frame 14 is shown in Figs. 5 and 5a.

Secured to the beams 14', 14' of the main frame is a cross-piece 112, to the center of which is secured the upwardly and downwardly projecting tubular supports 113 and 114. To the upper tubular support 113 is secured as by means of set screws 115, 115 the tubular support 116 for the bearings of the shafts of the bevel gears 48.

To the lower tubular support 114 is secured the casing 117 for the worm wheel 118 and the worm 119. The worm wheel 118 is electrically welded to the upper end of the rotary screw element 106. By means of a crank 120, the worm 119 may be rotated manually to effect rotation of

the worm gear 118 and the rotary screw element 106, and since the latter is threaded through the king post nut 105, the forward end of the drawbar frame 94 may be lifted or lowered by turning the crank 120.

It will also be seen by referring to Figs. 5 and 5a that the steering king post 121 is journaled on a vertical axis to the bolster 122. The king post 121 is preferably a seamless tube to the lower end of which is screw-threaded a collar 123 to serve as an enlarged head beneath the bolster 122. A screw 124, as shown in Fig. 5a, is threaded through the upper portion of the casing 117 and its inner end is provided with a pin which passes through registering openings in the tubular support 114 and the upper end of the king post 121. The screw 124 therefore co-operates with the tubular support 114 to hold both the casing 117 and the tubular king post 121 from turning relatively to the top frame plate 112. Where the king post 121 emerges from the top of the bolster 122 it is journaled in the bolster plate 125 which as shown in Fig. 5 is U-shaped with its upper ends welded to the beams 14', 14'. The vertical shaft 49 is journaled at its lower end portion in the insert or pilot bearing 121' which is welded to the interior of the lower end of the king post 121. The upper end of the shaft 49 is journaled in the bearing 116' which is secured to the bottom of the bevel gear housing 30 116.

Rotation of the shaft 49 to effect leaning of the front wheels may therefore be effected independently of the mechanism for lowering the front end of the drawbar frame 94. When the front wheels are moved to adjusted leaning positions, they are locked in such positions by the worm gearing 51, against any outward thrusts exerted laterally of the machine by operation of the mold-board when in steep bank-cutting position. Furthermore, when the front end of the drawbar has been adjusted to a lowered position, it will be locked there by the worm gearing 118, 119 shown in Fig. 5a.

The drawbar frame 94 comprises longitudinally extending angle irons 94', 94' which diverge at their rear end portions for rigid connection to the circular bearing-support 126 for the circle 92. Flexibly connected to opposite sides of the ring support 126, as indicated at 127 in Fig. 1, 50 are vertical hangers 128, 129, the upper ends of which are flexibly connected at 130, 131 to the radial crank arms 132, 133 at the forward ends of the longitudinal rock shafts 134, 135, as shown in Fig. 7. The forward ends of the rock shafts 55 134, 135 are journaled in bearings 136, 137 which are mounted at the outer ends of the cross-piece 138 secured rigidly to the tops of the beams 14' of the main frame 14.

The rear ends of the rock shafts 134 and 135 60 are journaled in bearings mounted on pedestals such as illustrated at 139 in Fig. 10, such pedestals being mounted on and secured rigidly to the downwardly sloping rear end portions of the beams 14'. The rear ends of the rock shafts 134, 65 135 are connected to worm gearing in the casings 140, 141 shown in Fig. 7, and to such worm gearing are connected the spaced-apart operating wheels 142, 143 located adjacent the operator's platform 26, as shown in Fig. 7.

Connected between brackets 144, 145, rigidly secured to the beams 14', and weight equalizing cams 146, 147 on the rock shafts 134, 135, are counterbalancing connections comprising the springs 148, 149 shown in Figs. 7 and 10. These 75

springs act against the weight of the drawbar frame and the parts mounted thereon, and therefore facilitate the operation of the wheels 142, 143 in adjusting the elevation and inclination of the mold-board.

Secured to the top of the casing 140, as shown in Figs. 4 and 7, is a bracket 150 for supporting a gear box 151 containing gearing for connecting the crank 152 to the upper end of the vertical shaft 153. The latter is connected by means of a universal joint 154, the link 155, and the universal joint 156 to worm gearing 157 for rotating the spur gear 158 which meshes with the transverse rack bar 159 mounted on the rear axle 160. The worm gearing 157 is mounted in the casing which is rigidly secured to the rear ends of the beams 14' and therefore when the crank 152 is rotated, rotary motion will be transmitted through the link 155 and the worm gearing 157 to the rack pinion 158. Rotation of the crank 152 will therefore cause the rack 159 to travel along the pinion 158, thereby shifting the rear end of the main frame relatively to the rear wheels. When the lateral adjustment of the rear end of the frame has been effected, the main frame will be locked in adjusted position relative to the rear wheels by the worm gearing 157, and consequently during operation of the mold-board while in steep bank-cutting position, the lateral working thrust on the main frame of the machine will not cause any movement of the main frame laterally relatively to the rear wheels.

The leaning of the rear wheels is effected by turning the crank 161 which is connected to gearing in a casing 162 supported on a bracket 150' mounted on top of the casing 141, as shown in Fig. 12. Extending from the bottom of the casing 162 is a vertical shaft 163 which is connected by a universal joint 164 to the link 165 (Fig. 12). The lower end of the link 165 is connected by means of the universal joint 166 to worm gearing in the casing 167, as shown in Figs. 4 and 12. The worm wheel shaft is secured to a pinion 168 which meshes with an arcuate rack 169, as shown in Figs. 4 and 12. The arcuate rack 169 is secured to the angle iron cross-piece 170, the ends of which are pivoted at 171, 172 to the upper ends of the bell crank arms 173, 174, the lower ends of which are pivoted at 175, 176 to the ends of the rear axle frame 160. The horizontal arms of the bell cranks pivoted at 175 and 176 serve as the axles for the rear wheels 15, 15'. When the mold-board is operating along the steep bank in almost upright position, as shown in the rear view of Fig. 12, it is desirable to lean the rear wheels as shown by the dotted lines 15', 15' so that the rims will be able to dig into the road surface and effectively resist the lateral thrust on the rear end of the machine during the operation of the mold-board along a steep bank.

The rear wheels are held locked in adjusted leaning positions by the worm gearing 167. It will thus be seen that at the rear end of the machine the worm gearing 157 locks the rear end of the main frame 14 against lateral movement relatively to the rear axle frame 160 during operation of the mold-board when in almost upright position, as shown in Fig. 12. At the same time the worm gearing 167 locks the leaning of the rear wheels in adjusted leaning positions. The front wheels are locked in adjusted leaning positions by the worm gearing 51 shown in Fig. 5. The worm gearings 157 and 167 are similar to the worm gearing 51 shown in Fig. 5. Although the worm gearing 157, 167 and 51 are each self-

locking and each individually operable, they all co-operate in resisting lateral thrusts on the machine during operation of the mold-board along a steep bank while having a high reach, as illustrated in Figs. 10 and 12.

In road building operations it is often highly desirable to widen the roadway by using a mold-board in bank-sloping position. If the mold-board can be moved only to a relatively small angle, the amount of material which must be cut down and then hauled away is much greater than when the mold-board can be moved to a steeper position to effect a given expansion in the width of the roadway. By being able to move the mold-board to an almost upright position, as shown in Figs. 10 and 12, a minimum amount of material need be cut down and hauled away for a given expansion in the width of the roadway. Where the nature of the ground operated upon is such that a steep sloping bank may be formed, it is preferred to use the machine at the greatest angle or steepest pitch as shown in Fig. 12, but it should be understood that the supporting and adjusting mechanism is capable of holding the mold-board at any of various angles between road grading position, such as that shown in Fig. 7, and the steep bank-cutting position, such as that shown in Fig. 12.

In order to secure adjustment of the mold-board through such a wide range of nearly 90°, I have arranged the hangers so that one may be expanded to be relatively long and the other contracted so as to be relatively short, and mount them so as to connect the main frame with the drawbar frame in co-operation with the flexible connections between the rear end of the drawbar frame and the rear portion of the main frame.

A sectional view of one of the hangers is shown in Fig. 11. As shown in Figs. 7 and 11, one of the upright hangers 128 is connected by the universal joint 130 to the crank arm 132 at the front end of the rock shaft 135. The universal joint 130 may comprise a pin 177 extending through an opening in the arm 132 and locked to the latter by the nut 178. The opposite end of the pin 177 is provided with a ball 179 which fits into a spherical socket 180 secured to a bracket 181 welded to the open ended tube 182 near one end of the latter. To the other end of the tube 182 is welded a cylindrical sleeve 183 which is provided with diametrically opposite openings registering with diametrically opposite openings in the tube 182.

The universal joint 127 which is located at the lower end of the extensible hanger 128 comprises a pin 184 locked to the ring 126 by means of the nut 185. A ball 186 fits in the spherical socket 187 which is secured rigidly to the lower end of the rod 188. The latter is provided with a plurality of spaced-apart openings 189 through 60 which is adapted to project the headed pin 190, as shown in Fig. 11. By removing the cotter pin 191, the pin 190 may be removed to free the rod 188 for sliding along the tube 182. In Fig. 11 the extensible hanger 128 is shown relatively short, whereas when it is extended to its full length it will appear as illustrated in Fig. 12. It is desirable to have the rod 188 fit rather snugly in the tube 182 so that it will cooperate therewith to resist the bending of the hanger 70 even when it is extended to the length shown in Fig. 12. As hereinafter more fully explained, during operation of the mold-board there is a longitudinal thrust on the hanger 128 which it is desired to resist without bending, and bending 75

is effectively resisted by having the rod 188 fit snugly into the tube 182. When the rod is in adjusted position in the tube 182, it is locked in such adjusted position by the pin 190 extending through one of the holes 189 and through the registered holes in the tube 182 and the ring 183. The pin 190 is kept from dropping out by the cotter pin 191.

As shown in Fig. 12, the hanger 129 also comprises an open ended tube 182', one end of which is connected by the universal joint 131 to the crank arm 133. For the sake of clearness, the rear view shown in Fig. 12 has assumed the rock shafts 134 and 135 as being horizontal and both ends at the same elevation, whereas in Fig. 10 the rock shafts 134, 135 slope downwardly and forwardly. In the event that these rock shafts are mounted in horizontal positions, the crank arms are lengthened as shown at 132' and 133' in Fig. 12.

The hanger 129, as shown in Fig. 12, comprises a relatively short tube 182', one end of which is connected by the universal joint 131 to the crank arm 133'. The tube 182' is open at both ends and the rod 188' extends entirely through the tube 182', and projects from both ends thereof. The rod is locked in the tube by means of a pin and hole construction as shown at 190 in Fig. 11. One end of the rod 188' is connected by the universal joint 127' to the drawbar frame 94. It should be understood that either rod 188 or 188' can project partially into its tube or entirely through the same. The tube 182' is made relatively short so as to afford ample space for movement of the universal joint 127' to the position shown in Fig. 12. The tube 182 is made relatively long so that the universal joint 127 may occupy the position shown in Fig. 12 and so that the drawbar frame and the circle may occupy an almost upright plane, as shown in Figs. 10 and 12. When the parts are adjusted to the positions shown in Fig. 12, the working thrust laterally of the machine will be effectively taken by the crank arm 133' on which a pull is exerted by the hanger 129, and the hanger 128 will resist an endwise thrust in cooperation with the arm 132'; also the tendency to bend the hanger 128 will be resisted by the projection of the rod 188 partially into the tube 182.

The flexible connections between the rear end of the drawbar frame 94 and the rear portion of the main frame 14 are adapted to enable adjustment of the mold-board to extended lateral positions so as to position the rear end of the drawbar for effective movement to an almost upright plane without interference of the main frame of the machine.

To the rear ends of the diverging angle bars 94', 94' at 192, 192 is pivoted a semi-circle 193 for adjustment relative to the drawbar frame on an axis which extends transversely of the machine when the mold-board is in road grading position. A cross-piece 194 rigidly connects the rear ends of the semi-circle 193, as shown in Fig. 8. A supporting plate 195 is pivotally connected at 196 to the center of the cross-piece 194. To the underside of the supporting plate 195 is secured a cylindrical socket 197 in which slidably fits the rod 198, the rear end of which is connected by the universal joint 199 to the elongated rack bar 200 which is mounted by means of spaced apart tongue and groove connections to slide transversely along the transverse inverted T-shaped support 201 which is rigidly secured to the under side of the rearwardly and downwardly sloping

beams of the main frame 14, as shown in Fig. 1, and also in Figs. 4 and 10.

As shown in Fig. 8, the universal joint 199 may be connected either through the bracket 202 or through the bracket 203 to the rack bar 200. When the joint 199 is connected to the bracket 202, as shown in Fig. 7, greater lateral shifting of the drawbar toward the right of the machine looking forward, may be obtained, whereas greater lateral shifting toward the left of the machine, looking forward, may be obtained when the universal joint 199 is connected to the bracket 203.

Releasable latch mechanism 204 is mounted on the radial support 195 and comprises a spring-pressed latch adapted to fit into any one of the notches 205, 206 so as to secure a rigid connection between the rack bar 200 and the semi-circular latch ring 193. As will be more fully hereinafter explained, the latch mechanism 204 may rigidly connect the radial support 195 to the semi-circular latch ring 193, whether the universal joint 199 is connected to the bracket 202 or to the bracket 203.

Meshing with the rack bar 200 is a pinion 207, as shown in Figs. 4 and 9. Worm gearing 208 is connected to the pinion 207 to drive the same, such worm gearing being mounted on the main frame 14 in the position illustrated in dotted lines in Fig. 4. By turning the crank 209 from the operator's platform 20, a vertical shaft 210 at the rear end of the machine may be rotated to operate the bevel gearing 211 illustrated in Fig. 9. This bevel gearing is connected by means of the universal joints 212, 213 and link 214 to the worm shaft 215. It will thus be seen that by rotating the crank 209 shown in Fig. 4, the pinion 207 shown in Fig. 9 may be rotated on a fixed axis relative to the main frame 14 and thus transmit rectilinear movement to the rack bar 200 which is mounted to slide along the straight support 201 secured to the bottom of the beams of the frame 14.

Various adjustments of the lateral position of the mold-board may be effected in cooperation with the hangers and the mechanism for operating the same. For instance, when the latch mechanism 204 locks the radial support 195 in the position shown in Fig. 8, the rack bar may be shifted toward the right, looking toward the front end of the machine. Then by releasing the latch mechanism 204, the rack bar may be returned while the support 195 freely pivots at 196, without causing any lateral shifting of the drawbar frame. By letting the latch move into one of the notches 205, an operating connection will be secured between the rack bar and the drawbar frame, and by again moving the rack bar toward the right, looking toward the front end of the machine, the rear end of the drawbar frame may be moved to a more extended lateral position relative to the main frame. In a similar manner, by connecting the universal joint 199 to the bracket 203 and using the latch mechanism in co-operation with the notch 205 and later with the notch 206, the rear end of the drawbar may be shifted to an extended lateral position at the other side of the machine. It should also be observed by referring to Fig. 10 that when the mold-board is in steep-bank-cutting position, the latch mechanism is associated with one of the notches 205 so that the support for the mold-board and the circle, formed by the drawbar and its connections to the main frame, will be upwardly arched. When the mold-board is on the other side of the machine in a steep bank-cutting position, the latch mechanism will be associated with one of the notches 206.

for a similar reason. It should be particularly noted that the worm gearing 208 shown in Fig. 9, is self-locking and therefore serves to effectively resist any tendency of the working thrust of the 5 mold-board when in steep bank-cutting position to move the rack bar 200 transversely of the machine.

When it is desired to use the mold-board on the other side of the machine from that shown 10 in Fig. 12, the hangers 128 and 129 may be interchanged and the rear end of the main frame shifted laterally to the other end of the rear axle frame. The hangers 128 and 129 are removable from the machine in a manner indicated in Fig. 11. That is to say, by removing the cap halves of the sockets 127 and 130. This may be done by loosening the nuts 221, 222 and removing the cap bolts 223, 224. The balls 186 and 179 may be left permanently connected to 20 the drawbar part 217 and to the crank arms 132 as shown in Fig. 11. Releasable pin and hole connections between the rods 188, 188' and the tubes 182, 182' are in the nature of releasable latch devices for permitting expansion or contraction of each of the hangers by operation of 25 the rock shafts 134, 135 in accordance with the desired position of the mold-board.

The adjustment of the mold-board from road-grading position to the upright blank sloping 30 position may best be understood by referring to Fig. 12 and considering the adjustments in effecting movement of the mold-board back from steep bank-cutting position to road grading position. If the rock shaft 134 moves the crank arm 35 132' in a clockwise direction, the lower end of the mold-board will be swung inwardly or toward the left, as viewed in Fig. 12, and the drawbar will rotate on its connections between the forward end and the rear end thereof with the 40 main frame, but at such time the pivot at 131 is fixed and therefore the pivot 127' can move only through an arc on a radius equal to the effective length of the hanger 129. The two hangers 128 and 129 therefore co-operate with 45 the connections between the ends of the drawbar frame and the main frame to rigidly hold the drawbar in a bank-sloping position but not at such a steep angle as that shown in Fig. 12. While the hanger 128 remains at its adjusted 50 length shown in Fig. 12, the crank arm 132' is effective through only an angle of nearly 180° to move the lower end of the mold-board toward the left. The upper end of the mold-board, however, may be lowered by moving the 55 crank arm 133' in a clockwise direction, as viewed in Fig. 12. While the crank arm 132' is diametrically opposite its position shown in Fig. 12, the hanger 128 is flexibly connected at its ends to the arm 132' and the drawbar frame. 60 However, when the arm 133' is moved in a clockwise direction as viewed in Fig. 12, the movement of the mold-board depends upon the position of the connections between the rear end of the drawbar and the rear portion of the main 65 frame. Movement of the arm 132' through approximately 180° in a clockwise direction, as viewed in Fig. 12, will move the universal joint 127 to a higher elevation so as to afford ample clearance for the lower end of the mold-board 70 to move under the machine. Movement of the arm 133' in a clockwise direction may continue to nearly 270° and be continually effective in lowering the upper end of the mold-board and effecting movement of the lower end of the mold-board transversely of the machine toward the 75

left as viewed in Fig. 12. In fact, the lowering of the upper end of the mold-board will be equal to the length of the arm 133' plus the distance between the universal joint 131 and the universal joint 127'. It will thus be seen that the hangers 128 and 129 may be locked in such extended positions that without making further adjustments, the mold-board may be moved from a position under the machine to a steep bank-cutting position beyond one side of the machine 10 by rocking the shafts 134, 135. Consequently, the operator while on the platform 20 may adjust the mold-board to various bank-sloping angles, or from low pitches to very high pitches. It can readily be seen by following the aforesaid 15 movements from the steep bank-cutting position shown in Fig. 12 to the position of the mold-board under the machine, that when in the latter position the machine may be readily transported. However, further adjustments in the extensions 20 of the hangers may be made for road grading purposes. It can readily be seen that when the mold-board is under the machine, the arm 132' may be moved in an anti-clockwise direction and thus let the mold-board contact with 25 the roadway, whereupon the hanger 128, after releasing the pin 190, may be adjusted to a desired length for road grading purposes and the pin 190 re-inserted. In a similar manner the hanger 129 may be adjusted in length by inserting a prop under the mold-board at that 30 side of the machine, releasing the pin 190 and operating the crank arm 133'. Inasmuch as the rod 188' extends through both ends of the tube 182' the effective length of the hanger 129 may 35 be made much longer than when it is adjusted to the length shown in Fig. 12. It can readily be seen by comparing Figs. 11 and 12 that the hanger 128 may have its effective length shortened and the hanger 129 may have its 40 effective length extended so that when the mold-board is in road grading position, both hangers are approximately the same length when the crank arms 132' and 133' extend radially from the rock shafts 134 and 135 in symmetrical relation to each other. 45

When the mold-board is in the steep bank-cutting position shown in Fig. 10, adjustments of the positions of the ends of the mold-board may be made by the circle operating gearing 103, 104 50 shown in Fig. 4. The mold-board may therefore be adjusted to the height of the bank to be cut, and when the mold-board is to be moved back to a position under the machine, its lower end may by the circle operating mechanism be moved 55 up off the ground so as to afford ample clearance. It should also be particularly noted that when the hangers 128 and 129 have been once adjusted to be respectively long and short, as shown in Fig. 12, a very wide range of bank-cutting positions 60 of the mold-board may be effected by rocking of the shafts 134 and 135 without further adjustments of the lengths of the hangers 128 and 129. But whenever desired, either hanger may be readily adjusted in length while the mold-board is 65 extraneously supported and only the shafts 134 and 135 actuated.

In view of the foregoing explanations, it will 70 become evident what adjustments can be made to change the mold-board from road-grading position such as that shown in Fig. 1 to elevated position in readiness for bank sloping operations. When in road-grading position the rock shafts 134 and 135 may be operated to lift the mold-board vertically and rectilinearly to transporta- 75

tion position. While in such elevated transportation position the mold-board may be supported by props placed under the end portions thereof and the latch pins 190 of the hangers then released. 5 The operator may then rotate the wheels 142 and 143 until the crank arm 132' of Fig. 12 is nearly vertical and extending upwardly and until the crank arm 133' is about vertical and extending downwardly, whereupon the pins 190 may be re-10 inserted and locked by means of the cotter pins 191 (Fig. 11) and the props under the mold-board removed.

The mold-board is now still in transportation position but it should be particularly noted that 15 without further adjustment of the lengths of the hangers the mold-board may be adjusted to various sloping bank-cutting positions including the nearly upright position shown in Fig. 12.

After the sustaining props are removed, the 20 rear end of the drawbar frame may be shifted to its maximum extent to one side of the machine, where the adjusting mechanism is locked by the worm gearing 208 (Fig. 9). Then all the 25 operator is required to do to adjust the pitch or slope of the mold-board, is to rotate the two wheels 142 and 143, with the assurance that whenever the mold-board is located it will be locked in adjusted position by the worm gearing 140, 141.

It should also be noted that the machine affords 30 a limited latitude of adjustment of the distance between the upright cutting plane of travel of the cutting edge of the mold-board and the path of travel of the adjacent wheels. This distance will depend upon the height to which the mold-board 35 is propped when horizontal and above the road surface, or it will depend upon the adjustment of the lengths of the hangers before the props are removed. However, such distance may also be varied when desired by changing the lengths of 40 the hangers while the mold-board is extraneously supported in bank-sloping position.

The lateral working thrust on the machine tending to skid the same sidewise away from the sloping bank will be greatest when the mold-board 45 is in the almost upright position shown in Fig. 12, but this lateral working thrust is effectually resisted and counteracted by the leaning of the front and rear wheels in such direction as to cause the edges of the rims remote from the sloping 50 bank to dig into the road surface. During such steep bank-cutting operations the steering mechanism shown in Fig. 6 is locked by the worm gearing 35 (Fig. 6), the front wheel leaning mechanism is locked by the worm gearing 51 (Fig. 5), the rear wheel leaning mechanism is locked by the worm gearing 167 (Fig. 12), the laterally 55 shifting mechanism for the rear end of the main frame is locked by the worm gearing 157 (Figs. 7 and 12), the laterally shifting mechanism for the rear end of the drawbar frame is locked by the worm gearing 208 (Fig. 9) and the latch mechanism shown in Fig. 8, and the front end of the drawbar frame is locked by the worm gearing 118, 119 (Figs. 5 and 5a).

65 During operation of the mold-board in high-lift position for operation on a steep bank, the scarifier may be up off the road surface as shown in Fig. 10, where it will be locked by the nut and screw elements 69, 70 shown in Fig. 2. The space 70 between the arms 82, 83 is ample to permit any desired adjustment of the drawbar frame at any time. While usually the scarifier is in operation only when the mold-board is in road-grading position, it may be adjusted to operative position by

the mechanism shown in Fig. 2 for operating during bank sloping operation by the mold-board.

If desired, the scarifier 79 may be omitted, as 5 shown in Figs. 3 and 4 placed end to end, but if included in the machine, the portions of the arms 83 extending downwardly from the beams 14', 14' should be bent outwardly sufficiently to provide ample space for the movements of the drawbar frame above referred to. Furthermore the scarifier structure may be made detachable without 10 interfering with the means shown in Figs. 1 and 2 for operating the front wheel leaning mechanism.

When the machine is operated along a steep 15 bank with the mold-board in an almost upright plane, as shown in Fig. 10, there is a tendency when the mold-board is dislodging rocks or roots of trees, for the rear end of the drawbar to be lifted from its adjusted position, but such tendency is effectually resisted by the connections 20 between the main frame and the front and rear ends of the drawbar frame.

As shown in Figs. 8 and 10, it is preferred to supply two notches 205 and two notches 206. If the work for the mold-board is unusually difficult at a steep bank, the latch 204 should be shifted to the upper notch 205, as viewed in Fig. 10, and the circle adjusted accordingly to provide proper clearance for the lower end of the mold-board. By flattening the upwardly extending 30 arched support for the circle and mold-board, the tendency will be less toward pulling the socket 197 off the rod 198. It may also occur in practice that the nature of the material in the steep bank is such that the mold-board when in the 35 position shown in Fig. 12, will have a tendency to be deflected from obstructions such as rocks or tree roots, farther into the bank in a direction away from the roadway. To counteract this tendency, the wheels may be leaned in directions 40 opposite to that shown in dotted lines at 15' in Fig. 12 to prevent skidding of the machine as a whole toward the bank.

It will also be seen by referring to Fig. 7 that the circular angle iron 126 is rigidly welded by 45 means of the cross-piece 216 and the vertical radial plates 217, 217, to the angle bars 94', 94' of the drawbar frame 94. The outer ends of the plates 217 are perforated to serve as anchorages for the pins 184 of the ball and socket joints 127, 50 55 127', as illustrated in Fig. 11.

The circle 92 is pivotally connected by means of the cross-piece 218 and the king-bolt 93 to the drawbar frame 94. Arcuate guide plates 219, 219 are welded to the cross-piece 218 adjacent 55 the outer ends of the latter, each in position to wipe the periphery of the horizontal flange of the ring 126. Welded to the inner face of the circle 92 and to the guide plates 219 is an arcuate latch plate 220 in position to extend over the 60 tops of the arcuate guide plates 219 and overlap the upper surface of the horizontal flange of the ring 126, as shown in Fig. 7. Thus guide grooves at diametrically opposite ends of the cross-piece 218 are formed to receive the horizontal 65 flanges of the ring 126.

The guide plates 219 engage the periphery of the horizontal flange of the ring 126, but the arcuate plate 220 overlaps the upper side of the flange of the ring 126, as clearly shown in Fig. 7. 70 Consequently the mold-board cannot be pulled away from the drawbar frame when steep bank-cutting operations are being performed. The interlocking connections at 219', 219' between the circle 92 and the ring 126 co-operate with the 75

king-bolt 93 and the latch mechanism 95' to hold the circle and the mold-board in their adjusted positions and prevent them from being pulled away from any portions of their supports attached to the angle iron 94' of the drawbar frame. It will therefore be evident that when the mold-board is adjusted for operation along a steep bank, as illustrated in Figs. 10 and 12, it will be held rigidly connected to the main frame 14 of the machine against movement relative thereto in any direction.

In the accompanying drawings where links, such as those designated 33, 34, 100, 155, 165, are shown in sections of different diameters, it should be understood that these links are extensible, one section being a rod square in cross-section, and the other section being tubular or having a complementary socket so that when rotary motion is given to the socket section, it will be transmitted to the rod section within the limits of adjustment in lengths of the links.

This application is a continuation in part of my copending application Serial No. 646,997, filed December 13, 1932, for an improvement in road graders, and the broader claims to common subject matter are presented in Serial No. 646,997.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a road grader, the combination with a frame, of a drawbar pivoted at its forward end to said frame, means comprising spaced hangers for adjusting the elevation of said mold-board and its inclination relative to the vertical, a support pivotally connected to the rear end of said drawbar on a transverse axis, a rearward extension from said support in lateral angular relation to the drawbar, and laterally shifting mechanism mounted on said frame and comprising spaced-apart brackets either of which is adapted to be selectively connected to the rear end of said angular extension.

2. In a road grader, the combination with a vehicle frame, of a drawbar universally pivoted at its forward end to said frame, a mold-board adjustably carried by said drawbar, means comprising extensible hangers at the sides of said frame for adjusting the elevation of said mold-board and its inclination relative to the vertical, one hanger comprising a rod extending through a relatively short tube and the other hanger comprising a rod extending into a relatively long tube, the universal pivot at the forward end of said drawbar permitting said drawbar to be moved relatively to said frame to an almost vertical plane to support the mold-board for operation on a nearly vertical bank spaced laterally from the path of travel of the vehicle, and means extending rearwardly from said drawbar to said frame for holding the drawbar at an adjusted angle relative to the line of draft and to operate with the drawbar to afford an upwardly extending arched support for the mold-board when adjusted to such upright bank cutting position.

3. In a road-grading machine, the combination with a supporting frame, of a road working

implement adjustably mounted on said frame, means comprising an extensible thrust rod comprising enclosed nut and screw elements connected to said road working implement to adjust the same relative to said frame, a tubular cross-brace on said frame, an elevated cross-support rearwardly of said tubular cross-brace, longitudinal bracing plates connecting said tubular cross-brace to said cross-support, a thrust bearing for said rod, and trunnions between said bearing and said plates for vertical oscillation of said bearing between said plates.

4. In a road-grading machine, the combination with a main frame, of a drawbar frame, a mold-board, a circular angle iron track secured to said drawbar frame, mechanism comprising a king pin for pivotally connecting the circle to said drawbar frame concentric with said circular track, interlocking guiding mechanism between said circle and said circular track at diametrically opposite sides of said circle, mechanism for supporting said circle and said mold-board for operation of the latter on an almost upright bank at one side of the path of travel of the machine, and means for preventing laterally skidding of the machine when operating along such steep bank.

5. In a road-working machine, the combination with a main frame, of a drawbar frame, a mold-board carried by said drawbar frame, a rack-bar, a support mounted on said main frame for the sliding of said rack-bar laterally of said main frame, a semi-circular latch member having spaced-apart notches and pivotally connected to the rear end of said drawbar frame, a plate pivoted to said latch member concentric with the rear periphery thereof, a releasable latch carried by said plate and adapted to engage any one of said notches in said latch member, a socket carried by said plate, a rod slidable into said socket, a universal joint between the rear end of said rod and said rack bar, and means comprising self-locking worm gearing for shifting said rack bar laterally to effect lateral shifting of the rear end of the drawbar frame.

6. In a road grader, the combination with a vehicle comprising a supporting frame, of a supplemental frame, a mold-board carried by said supplemental frame, a universal connection between the forward end of said supplemental frame and said supporting frame to permit movement of said supplemental frame to a position where the mold-board cutting edge will occupy an upright plane, adjustable connections between the rear end of said supplemental frame and said supporting frame to secure an upwardly arched support for the mold-board when its cutting edge is in such upright plane, and mechanism comprising extensible hangers one comprising a rod extending through a relatively short tube and the other comprising a rod extending into a relatively long tube, said hangers being between the supporting frame and said supplemental frame and adapted to co-operate with the connections between said supplemental frame and said supporting frame to support the mold-board in position for operation along an upright bank at one side of the machine.

7. In a bank-sloping machine, the combination with a vehicle comprising a supporting frame, a mold-board, a drawbar for carrying said mold-board, a pivotal connection between the forward end of said drawbar and said supporting frame, laterally shiftable mechanism on said supporting frame rearwardly of the rear end of said draw-

bar, adjustable connections between the rear end of said drawbar and said laterally shiftable mechanism to secure an upwardly arched support for the mold-board when the latter is at 5 either side of said supporting frame, and mechanism comprising extensible hangers connected between said supporting frame and said drawbar, one of said hangers comprising a rod extending through a relatively short tube and the other 10 hanger comprising a rod extending through a relatively long tube, said hangers being adapted to cooperate with said laterally shiftable mechanism and the adjustable connections between the same and the rear end of said drawbar to effect adjustment of the mold-board from a position under 15 said frame to a steep bank-cutting position spaced laterally from either side of said supporting frame.

8. In a bank-cutting machine, the combination 20 with a vehicle comprising a supporting frame, of a mold-board, a supplemental frame for carrying said mold-board, a pivotal connection between one end of said supplemental frame and said supporting frame, laterally shiftable mechanism on 25 said supporting frame spaced from the other end of said supplemental frame, adjustable connections between such laterally shiftable mechanism and the adjacent end of said supplemental frame adapted to co-operate with said supplemental frame to secure an upwardly arched support for the mold-board when the latter is in steep bank-cutting position, and mechanism comprising spaced-apart hangers one having a rod extending through a relatively short tube and the other 30 having a rod extending through a relatively long tube for co-operating with said upwardly arched support to move the mold-board to various steep bank-cutting positions with the cutting edge of the mold-board entirely beyond the path of travel 35 of the vehicle.

9. In a road grader, the combination with a 40 vehicle comprising a supporting frame, of a road-working implement, a drawbar for carrying said implement, a pivotal connection between the front end of said drawbar and said frame, means for adjusting the elevation of said pivotal connection relative to said frame, a laterally shiftable bracing structure extending longitudinally of said frame between the rear end of said drawbar and 45 said frame, said bracing structure being flexible as to adjustability, and means comprising spaced-apart hangers between said frame and said drawbar to co-operate with the connections between the ends of said drawbar and said frame to adjust 50 the road-working implement to bank-sloping position at one side of said frame, the lowering of the pivotal connection affording ample freedom of movement of said drawbar relatively to said frame and said bracing structure co-acting with 55 said hangers and said pivotal connection during operation of the implement to hold the latter to its work.

10. In a road grader, the combination with a 60 wheel-supported frame, of a drawbar pivotally connected at its forward end to said frame, a mold-board adjustably carried by said drawbar, means for lifting the rear end of said drawbar on its pivotal connection with said frame, an extensible connection between the rear end of said 65 drawbar and said frame, and means comprising releasable latch mechanism associated with a latch member having a plurality of notches on each side of the center thereof for locking said extensible connection at an adjusted angle relative to said drawbar.

11. A road-working machine comprising the combination with a vehicle comprising a frame, of a mold-board, a drawbar for carrying said mold-board, a pivotal connection between the front end of said drawbar and said frame, mechanism between said frame and the rear end of said drawbar for effecting shifting of the mold-board laterally of said frame, means comprising extensible hangers adapted to co-operate with said shifting mechanism to effect adjustment of 10 said road-working implement to a steep bank-cutting position at one side of said frame, manually operated self-locking actuating mechanisms respectively connected to said hangers, manually operated self-locking means for operating said shifting mechanism, and self-locking mechanism for adjusting the elevation of the said pivotal connection between the front end of said drawbar and said frame so that when the pivot at the front end of the drawbar is lowered ample clearance under the frame will be afforded for movement of the drawbar and the mold-board to steep bank-cutting position, said extensible hangers and the connections between said frame and the ends of said drawbar serving as the sole support 15 for the drawbar and the mold-board when the latter is in its steep bank-cutting position.

12. A road working machine comprising the combination with a wheel-supported frame, of a drawbar pivotally connected at its forward end 20 to said frame, a mold-board adjustably carried by said drawbar, means for lifting the rear end of said drawbar on its pivotal connection with said frame, a laterally shifting device on said frame, an extensible connection between the rear end of said drawbar and said laterally shifting device, and means comprising releasable spring-pressed 25 latch mechanism associated with a latch member having a plurality of notches for locking said extensible connection at an adjusted angle relative to said drawbar.

13. In a road grading machine, the combination 30 with a supporting frame, of a road working implement adjustably mounted on said frame, means comprising extensible telescopic translating mechanism connected to said road working implement to adjust the same relative to said frame, a tubular cross-brace on said frame, a cross support spaced rearwardly from said tubular cross-brace and secured to said frame, reinforcing structure between said cross support and said tubular cross-brace, trunnions mounted on said 35 cross support and connected to said reinforcing structure, and bearings extending laterally from said extensible telescopic translating mechanism 40 in position to fit said trunnions.

14. A hanger for road building machines, comprising, in combination, an elongated tube open at both ends, a rod having a slideable guiding fit in said tube to provide an elongated slide bearing, a 45 transverse pin extending through said tube and one of a series of holes in said rod for holding the latter in adjusted relation to said tube including a position of the rod extending entirely through said tube, a ball and socket joint connected to said tube, an additional ball and socket joint connected to said rod, and means for detachably connecting said ball and socket joints to spaced-apart elements of a road-building machine.

15. In a road building machine, the combination 50 with a wheel-supported frame, of a road-working implement, and means for adjustably supporting said road working implement relative to said frame comprising an open ended tube having a rod fitted therein and slideable there- 55

through to project beyond both ends thereof, and flexible connections to the tube and to the rod.

16. In a bank-sloping machine, the combination with a wheeled supporting frame, of a drawbar frame, a road-working implement carried by said drawbar frame, and means for adjusting the road-working implement to steep bank-cutting position comprising spaced-apart hangers the upper relatively short in its effective length and the lower relatively long when the road-working implement is in steep bank-cutting position, the upper hanger having a rod extending through a relatively short tube and the lower hanger having a rod extending into a relatively long tube.
17. A road working machine comprising the combination with a main frame, of a drawbar frame, a road working implement carried by said drawbar frame, a semi-circular latch member having spaced-apart notches and pivotally connected to the rear end of said drawbar frame, a support pivoted to said latch member concentric with the rear periphery thereof, a releasable latch carried by said support and adapted to engage any one of said notches in said latch member, a socket carried by said support, a rod slidable into said socket, a laterally shifting device carried by said main frame, and a universal joint between the rear end of said rod and said laterally shifting device.
18. A road working machine comprising the combination with a main frame, a drawbar frame, a road working implement carried by said drawbar frame, a semi-circular latch member having spaced-apart notches and pivotally connected to the rear end of said drawbar frame, a support pivoted to said latch member concentric with the rear periphery thereof, a releasable latch carried by said support and adapted to engage any one of said notches in said latch member, a socket carried by said support, a rod slidable into said socket, lateral shifting mechanism carried by said main frame, spaced-apart brackets connected to said lateral shifting mechanism, and means comprising a universal joint for connecting said rod to either of said brackets.

19. In a road building machine, the combination with a vehicle comprising a supporting frame, of a drawbar connected at its ends to the front and rear portions of said frame, a mold-board carried by said drawbar, spaced-apart hangers one comprising a rod connected to said drawbar and slidable through a relatively short tube and the other comprising a rod connected to said drawbar and slidable into a relatively long tube, mechanism supporting said hangers in position to co-operate with the end connections between said drawbar and said frame to support the mold-board in steep bank-cutting position at one side of the machine with the hanger having a short tube in elevated position and with the hanger having the long tube extending diagonally downward from that side of the machine remote from the mold-board, and means for actuating said hangers to adjust the mold-board to such steep bank-cutting position.

20. In a road working machine, the combination with a main frame, of a supplemental frame, a road working implement carried by said supplemental frame, an adjustable flexible connection between the forward end of said supplemental frame and said main frame, laterally shifting mechanism on said main frame, an extensible connection extending rearwardly from and longitudinally of said supplemental frame to said laterally shifting mechanism, and spaced-

apart attaching devices on said laterally shifting mechanism either of which is adapted to have flexibly connected thereto the rear end of said extensible connection.

21. In a road working machine, the combination with a main frame, of a drawbar frame flexibly connected at one end to said main frame, laterally shifting mechanism spaced longitudinally of the machine from the other or free end of the drawbar, an extensible connection extending from the free end of the drawbar longitudinally of the machine toward said laterally shifting mechanism, and spaced-apart attaching devices on the laterally shifting mechanism either of which is adapted to have connected thereto the rear end of said extensible connection.

22. In a road working machine, the combination with a main frame, of a drawbar flexibly connected at its forward end to said main frame, extensible hangers between said main frame and said drawbar, a rack bar on said main frame, spaced-apart attaching devices on the rack bar and movable therewith respectively to opposite sides of the machine, and an extensible connection extending rearwardly from the rear end of said drawbar longitudinally of the machine to either of said attaching devices, said extensible connection comprising a link structure flexible on a horizontal transverse axis in response to operation of said hangers when the drawbar is under said main frame but rigid against lateral movement when connected to said rack bar.

23. A road working machine comprising a road working implement, a frame for carrying the same, laterally shifting mechanism including an elongated member mounted for movement transversely of the machine, spaced attaching devices on said elongated member, and a connecting structure extending rearwardly from said frame longitudinally of the machine to either of said attaching devices, said structure being flexible for movement of the said frame in elevation when the road working implement is adjacent the road surface under the machine, but said structure being rigid against flexure laterally when said elongated member is moved transversely of the machine while attached by means of one of said attaching devices to the rear end of the said connecting structure.

24. In a road grading machine, the combination with a supporting frame, of a drawbar, a mold-board carried by said drawbar, a flexible connection between the forward end of said drawbar and said frame, rearward extending connections between the rear end of said drawbar and said supporting frame rigid against flexure laterally relative to said drawbar but flexible for variation in elevation of the rear end of the drawbar when the mold-board is under said frame, mechanism comprising hangers connected to said drawbar to vary the elevation and transverse inclination of said mold-board as permitted by the aforesaid flexibility of said rearward extending connections, and shifting mechanism on said supporting frame and comprising spaced-apart attaching means to the rear end of said connections to shift the mold-board laterally while said connections are rigid against lateral flexure as aforesaid, said lateral shifting mechanism being adapted to co-operate with said hangers and the elevating mechanism connected thereto to move the mold-board to steep bank-sloping position at one side of said machine where said rigidity of said connections serves to afford a rearwardly extending rigid support for the rear end of the

drawbar on the supporting frame when the mold-board is operating in bank-sloping position.

25. A road grading machine comprising the combination with a supporting frame, of a drawbar connected at its forward end to said supporting frame, a mold-board carried by said drawbar, connections extending rearwardly from the rear end of said drawbar longitudinally thereof and rigid against flexure laterally relative to said drawbar but flexible for variation in elevation of the rear end of the drawbar when the mold-board is under said supporting frame, mechanism comprising extensible hangers adjustable as to length and connected to said drawbar to vary the elevation and transverse inclination of said mold-board as permitted by the aforesaid flexure of said connections, and shifting mechanism on said supporting frame comprising a transversely movable member having spaced-apart attaching means to the rear ends of said connections to shift the mold-board laterally while said connections are rigid against lateral flexure as aforesaid, said laterally shifting mechanism being adapted to co-operate with said extensible hangers and the elevating mechanism connected thereto to move the mold-board to steep bank-sloping position at one side of said machine where said rigidity of said connections strengthens the support of the mold-board when operating in bank-sloping position.
- 30 26. A road working machine comprising the combination with a vehicle frame, of a mold-board, a drawbar for carrying said mold-board, a pivotal connection between the front end of said drawbar and said frame, mechanism extending rearwardly from said drawbar and longitudinally thereof to said vehicle frame for effecting shifting of the mold-board laterally of the said frame, means comprising extensible hangers adapted to co-operate with said shifting mechanism to effect adjustment of said mold-board to a steep bank-cutting position at one side of said frame with the greater portion of the mold-board extending laterally beyond the path of travel of the vehicle, and mechanism independent of said extensible hangers for adjusting the elevation of the front end of the drawbar to afford ample clearance for movement of the drawbar from under said frame to bank-sloping position.
- 35 27. A road working machine comprising the combination with a vehicle frame, of a mold-board, a drawbar for carrying said mold-board, a pivotal connection on a vertical axis between the front end of said drawbar and said frame, mechanism between said frame and the rear end of said drawbar for effecting shifting of the mold-board laterally of said frame, means comprising extensible hangers adapted to co-operate with said shifting mechanism to effect adjustment of said mold-board to a steep bank-cutting position at one side of said frame, and mechanism independent of said extensible hangers for adjusting the elevation of the front end of said drawbar along said upright axis to enable said drawbar to have ample clearance under the frame for movement of the mold-board from under said frame to said steep bank-cutting position.
- 40 28. A road working machine comprising the combination with a vehicle frame, of a mold-board, a drawbar for carrying said mold-board, a steering unit pivotally connected to the front end of said frame on a vertical axis, connections between the front end of said drawbar and said frame on rectangularly related axes one of which coincides with said upright axis, mechanism between said frame and the rear end of said draw-
- bar for effecting shifting of the mold-board laterally of the said frame, means comprising extensible hangers adapted to co-operate with said shifting mechanism to effect adjustment of said mold-board to a steep bank-cutting position at one side of said frame, and mechanism independent of said extensible hangers for adjusting the elevation of the front end of said drawbar along said upright axis to afford ample clearance for movement of the drawbar from under said frame to one side of said frame for said steep bank-cutting position of the mold-board.
- 45 29. A road machine comprising a main frame; a tool positionable beneath said main frame; spaced connections between said main frame and said tool including lift links adjustable as to length; and mechanism co-operable with said lift links for positioning and maintaining said tool at an angle to one side of said main frame comprising an extensible link connected with said tool, and a second member mounted for shifting movement on said main frame transversely thereof and having a plurality of fastening stations thereon to any selected one of which said extensible link is adapted for connection, one of said fastening stations serving as a point of connection for said link beyond one side of said main frame, and the other fastening station serving as a point of connection for said link beyond the other side of said main frame, and means for shifting said second member laterally relatively to the main frame to effect movement of said fastening stations beyond the sides of the main frame and thereby through said link connection to said drawbar shift the said tool into position to project well beyond the sides of the main frame.
- 50 30. A road machine comprising a vehicle frame; a supplemental frame connected thereto; a grader blade mounted on said supplemental frame; spaced connections between said main frame and said supplemental frame including spaced arms each mounted on said vehicle frame for rotation about a longitudinal axis, and lift links each adjustable as to length and pivotally connected both to said arms and to said supplemental frame; and mechanism co-operating with said lift links for positioning and maintaining said supplemental frame with the grader blade thereon at a high angle to one side of said vehicle frame comprising an extensible link connected to said supplemental frame, and a second member mounted for shifting movement on said vehicle frame transversely thereof and adapted to be shifted to positions projecting beyond the sides of said vehicle frame, said second member having a plurality of fastening stations thereon to any selected one of which said extensible link is adapted for connection, either of said fastening stations serving as a point of connection for said extensible link for normal working operation of said grader blade beneath said vehicle frame, and one of said fastening stations serving as a point of connection for said link during high angle positioning of said grader blade on one side of the vehicle frame and the other fastening station serving as a point of connection for said extensible link during high angle positioning of said grader blade on the other side of the vehicle frame.
- 55 31. A road working machine comprising a vehicle frame; a tool supporting frame positionable beneath said vehicle frame; a draft connection for said tool supporting frame having a connection with said vehicle frame; spaced connections between said vehicle frame and said tool

supporting frame including lift links each adjustable as to length; each of said lift links comprising a tubular member, a second member telescoping within said tubular member, one of said members having apertures spaced along the length thereof and the other of said members having an aperture adapted to be aligned with a selected one of said spaced apertures, and a securing member adapted to be inserted through any selected aligned apertures in said members; and mechanism constructed to be rigid against lateral flexing independently of said lift links and co-operable with the latter for positioning and maintaining said tool supporting frame at a high angle 10 at one side of the vehicle frame, said means rigid against lateral flexing comprising lateral shift mechanism between said tool supporting frame and said vehicle frame including a substantially rigid member mounted for transverse movement 15 on said vehicle frame and having spaced fastening stations thereon, and extensible link structure connecting said tool supporting frame to a selected one of said fastening stations, said extensible link structure extending rearwardly from said tool supporting frame to said vehicle frame and being rigid against lateral flexing to enable movement of said rigid member transversely of the vehicle frame to impart lateral movement to said tool supporting frame, 20 such rigidity against lateral flexing also enabling said extensible link structure to support the tool supporting frame in steep bank sloping position on the vehicle frame rearwardly of the tool supporting frame in co-operation with said extensible 25 hangers.

32. A road machine comprising a vehicle frame; a tool supporting frame positionable beneath said vehicle frame and having a draft connection with the latter; spaced connections 30 between said vehicle frame and said tool supporting frame including lift links each adjustable as to length; and means constructed to be substantially rigid against lateral flexing independently of the lift links and co-operable with the latter for positioning and maintaining the tool supporting frame at a high angle at one side of the main frame, said means comprising lateral shift mechanism between said tool supporting frame and said vehicle frame, said laterally shifting mechanism including a substantially rigid member mounted for transverse movement on 35 said main frame rearwardly of the said tool sup-

porting frame and having spaced fastening stations thereon, and link structure connecting a selected one of said fastening stations to said tool supporting frame, said link structure being rigid against lateral flexing to enable transverse movement of said rigid member to shift laterally the rear end of the tool supporting frame. 5

33. A road machine comprising a vehicle frame; a tool supporting frame positionable beneath said vehicle frame and having a draft connection with said vehicle frame; spaced connections between said tool supporting frame and said vehicle frame including lift links each adjustable as to length; and means constructed to be substantially rigid against lateral flexing 10 and co-operable with said lift links for positioning and maintaining said tool supporting frame at a high angle at one side of said vehicle frame, said means being additional to the lift links and in itself without said lift links rigid against lateral flexing because comprising lateral shift mechanism between said tool supporting frame and said vehicle frame including a substantially rigid rack bar mounted for transverse movement on said vehicle frame and having a fastening 15 station adjacent each end thereof adapted upon movement of the rack bar to be projected beyond the associated side of said vehicle frame, and link structure extending rearwardly from said tool supporting frame to a selected one of 20 said fastening stations, said link structure comprising telescopically connected members to render said link structure extensible, one of said members being connected to one of said fastening stations, said link structure not including a 25 rigid link member because of the telescopic extension as aforesaid but said link structure being nevertheless rigid against lateral flexing to enable lateral movement of the rack bar to impart lateral movement to the tool supporting frame; 30 and means for actuating said rack bar comprising a pinion meshing with the rack thereon to effect lateral shift of the said link structure and said tool supporting frame, the co-operation of the extensible lift link as aforesaid being to 35 effect movement of the tool supporting frame to steep bank cutting position at one side of the frame where said rearwardly extending link structure now resisting downward flexing aids in the support of the tool supporting frame on said 40 vehicle frame. 45 50
